CLAIM

The ornamental design for a tooth mold retaining frame, as shown and described.

DESCRIPTION

FIG. 1 is a perspective view of a tooth mold retaining frame showing my new design;

FIG. 2 is a front view of the design;

FIG. 3 is a rear view of the design;

FIG. 4 is a right side view of the design;

FIG. 5 is a left side view of the design;

FIG. 6 is a top view of the design;

FIG. 7 is a bottom view of the design; and,

FIG. 8 is another perspective view of a tooth mold retaining frame shown in an environment.

The dash-dot-dash broken line portion in FIG. 8 is included to show unclaimed subject matter only and forms no part of the claimed design.
